UNITED STATES PATENT OFFICE.

EMORY I. NICHOLS, OF SAN FRANCISCO, CALIFORNIA, ASSIGNOR, BY MESNE ASSIGNMENTS, TO IRVINE STEWART AND FRANK E. TREMPER, OF SAME PLACE.

ELECTRIC ROTARY PUMP.

SPECIFICATION forming part of Letters Patent No. 425,106, dated April 8, 1890.

Application filed March 13, 1889. Serial No. 303,161. (No model.)

To all whom it may concern:

Be it known that I, EMORY I. NICHOLS, of the city and county of San Francisco, and State of California, have invented an Improvement in Electric Rotary Pumps; and I declare the following to be a full, clear, and exact description thereof.

My invention relates to the class of rotary pumps.

10 The object of my invention is to provide a simple and effective electrically-driven pump; and to this end my invention consists in wrapping the revoluble shell of a rotary pump with wire in such a manner as to form an armature of an electric motor.

15 Referring to the accompanying drawings, Figure 1 is a vertical section of my electric rotary pump. Fig. 2 is a horizontal section of same, the wire-wrapping in both figures 20 being but partially shown.

25 A is a fixed hollow shaft, one end of which forms the inlet-port *a*, and the other end forms the outlet-port *a'*. The shaft is formed with an eccentric center *B*, having the en- 30 circling port *b*, communicating with the inlet and discharge ports, as shown in Fig. 2.

Upon shaft *A* is mounted and adapted to revolve the shell *C*, which, inclosing the eccentric center *B*, forms at one part or line an 35 abutment *b'* and at the remaining portion a water-space *b*². Suitable packing and stuffing boxes are used between the parts.

In the shell *C* are the swinging pistons *D*, controlled by springs *d* and operating against 40 the circumference of the eccentric center. This forms a rotary pump, the operation of which, upon revolving the shell *C*, is obvious. To revolve this shell I make the pump, or a rim connected therewith, form the core 45 of an armature of an electric motor. This is done by properly wrapping the shell with wire *E*, so as to form an electric armature. This wrapping may be done in any suitable manner, and it may be directly on the shell; or, as here shown, it may be upon a rim *F*, carried by the shell.

I have not herein deemed it necessary to show any of the parts of an electric motor, as they do not form part of my invention. It is sufficient, therefore, to show an electric 50 armature, of which the pump or its rim *F* forms its core, the position and function of the armature in an electric motor being well known.

I do not confine myself to the particular 55 construction and arrangement of the pump parts herein shown, as these may be varied to any extent without changing the principle of my invention, which is to construct an electric-motor armature of which a rotary 60 pump or a connected part forms its core.

The operation of the device is as follows: The electric current passing through the brushes (not here shown) and energizing the armature, the latter is revolved by the field-magnets. (Not shown.) The shell *C* is thereby rotated, and, through its pistons, sucks in and forces out the water. An advantage of this form of armature lies in the fact that by reason of the hollow journals through which 70 the water is passing there is no liability to that drawback of hot journals to which high-speed electric motors are subject.

Having thus described my invention, what I claim as new, and desire to secure by Letters Patent, is—

An improved rotary pump comprising a fixed hollow shaft having an inlet and outlet port, said shaft having also an eccentric center with an encircling port communicating 80 with the inlet and outlet ports, a rim formed with the revoluble shell, and a wrapping of wire upon the rim to form of said shell an electric-motor armature, as herein described.

In witness whereof I have hereunto set my 85 hand.

EMORY I. NICHOLS.
